BRACELET CATCH

Edwin A. Neugass, New York, N. Y.

Application November 4, 1933, Serial No. 696,608

9 Claims. (Cl. 63—4)

This invention relates to articles of jewelry, such as bracelets, circlets, necklaces and for clasp constructions therefor.

It is an object of my invention to provide ornamental articles, such as costume jewelry, in which

5 such ornamental materials as plastics, of which phenol formaldehyde resins, urea resins and similar synthetic resins constitute the major material, whereby bracelets, circlets, necklaces, pendants, 10 earrings and brooches may be made.

In general, it is an object of my invention to provide costume jewelry from ornamental plastics and similar materials which are difficult to have associated therewith metallic clasps and to so 15 form the same that highly ornamental and pleasing configurations are formed with the minimum amount of labor and operations, while attaining security of attachment for holding these articles in position.

20 It is still further contemplated as an object of my invention to provide costume jewelry made of plastics, such as synthetic resins, wood, glass and precious and semi-precious stones, a clasp construction whereby these elements may be formed into bracelets, circlets, such as necklaces and 25 rings or pendants, to obtain with the materials of the character described not only novel configurations, but also secure clasping means which avoid the difficulty in labor in attachment of 30 metallic parts for securely holding these articles of jewelry in position upon the wearer.

It is still further contemplated by my invention to provide costume jewelry made from plastics, wood, glass, semi-precious and precious stones, in 35 the form of a chain or link construction whereby pleasing color schemes may be obtained and to include in costume jewelry of this character, means for clasping the parts together for attachment to the wearer, and includes such clasping 40 means without detracting from the ornamental appearance of the article, while securing efficient attaching means of simplicity in construction and operation.

To attain these objects and such further objects as may appear herein or be hereinafter pointed out, I make reference to the accompanying drawing, in which—

Figure 1 is a side view of a link bracelet made in accordance with my invention;

50 Figure 2 is an enlarged fragmentary view thereof, with the outer links removed to show the clasp construction;

Figure 3 is an interior view thereof;

55 Figure 4 is an enlarged fragmentary section taken through the clasp;

Figure 5 is an enlarged fragmentary view for a link and clasp for another embodiment of my invention.

Making reference to the drawing, it is contemplated by me to provide costume jewelry from such highly ornamental materials as may be made from transparent or translucent or opaque synthetic resinous materials, such as phenol formaldehyde condensation products, urea condensation products, or similar plastics, which lend 5 themselves readily to pigmenting or tinting to resemble natural precious or semi-precious stones, and to form these elements into costume jewelry, such as bracelets, circlets, necklaces, pendants, 10 earrings and brooches, in which the elements 15 thereof comprise individually connected links in the form of a chain. An assembly of similarly colored or contrasting colored links may be formed into the articles above referred to, to obtain a 20 pleasing and ornamental effect. While precious 25 and semi-precious stones and plastics have been utilized for this purpose, these have been combined into settings of metal which, in turn, form a basis for the link structure and the clasp. Such 30 settings, however, detract from the appearance of 35 the ornamental article, in the form of jewelry, aside from the cost of shaping and forming these 40 metallic settings. Accordingly, an article of 45 jewelry contemplated by me, as exemplified in the drawing, for purposes of making a bracelet 10, 30 is constructed from individual links 11 each of 35 which are formed with orifices 12 and 13. These 40 may be arranged in spaced relationship to form 45 bifurcations 14 and between such bifurcations 50 there are inserted corresponding links 15 of the 55 general contour as shown by the link 11, and are 60 also formed with orifices 16 and 17. The orifices, 65 in the case of the links 11 and 15, are spaced 70 from the ends 18 and 19 respectively, to leave 75 projecting ends 20 and 21 respectively, of a length 80 slightly less than one-half of the distance 85 between the orifices 12 and 13, for purposes which 90 will appear more clearly as this description 95 proceeds, and further, to form more or less a continuous 100 surface of the links 11 and 15 respectively. 45 When these links are provided in overlapping 105 relationship, a pin 22 is inserted through the 110 aligned orifices 12 and 16, and 13 and 17 115 respectively, one end of the pin being provided with 120 an enlarged head 23. The opposite end of the 125 pin may then be riveted at 24 to completely 130 assemble the spaced links 11 and the interposed 135 links 15. It will be understood that though there 140 has been described a chain for forming the bracelet, 145 comprising three layers of links arranged in 150

overlapping relationship, as many of these links may be provided, in accordance with the width of the bracelet that is to be formed, and accordingly, the pins connecting these links may be increased to assemble the link elements of such increased number.

A construction of this character may be formed from arcuately curved link elements 11 and 15 respectively. However, where the contour of these link elements is rectilinear, curvature may be imparted by the pivotal action of these individual links about the pins, holding the links together.

In order to provide a clasp for the circlet, in the form of the bracelet just described, I prefer to provide one of the link elements 25 with clasp means. This link corresponds in contour and position in all respects similar to the link 15. However, adjacent one end 26, the orifice 27 is directed inwardly towards the lateral wall to form a slit 28. Where the links are small and of rather fragile material, particularly the synthetic plastic materials previously referred to, a sheathing 29 is shaped over the edge of the link and is held to the opposite faces by pins 30, passing through orifices 31. This sheathing may be made of soft metals, such as silver, gold, platinum, where more expensive jewelry is to be provided, or copper or brass plated with desirable more precious metals, for the more inexpensive articles of jewelry. The sheathing thus provided adjacent the slit 28 is formed inwardly with a loop 32, fitting snugly within the slit at its bottom portion, but constricted adjacent its entrance portion to provide resilient jaws 33. These jaws are constricted to be spaced from each other for a distance less than the diameter of the pin 22.

With a clasp of the character described, entrance is effected merely by pressing the link carrying the slit against the pin 22. For removal, the linkage is pinched to tilt the ends 21 and 26 out of the plane of the outer surfaces of the links, as more clearly shown in Figure 4. The exposed projecting ends 21 and 26 respectively, provide convenient manipulating means for applying manual pressure and serve to readily disengage the slit and pin from each other. Normally, the tension of the links against each other will serve to hold the pin in engagement with the slit formed in the link 25.

Where the links are made of heavier stock, the sheathing 29 may be omitted and the clasp may be formed in accordance with the embodiment illustrated in Figure 5. In this embodiment, a link 25a is provided with orifices as in the embodiments previously described. Where, however, this form of link is to serve as a clasp, a drill hole 27a is provided longitudinally of the axis of the circlet where the link is associated in this type of jewelry. The orifice is then provided with a slit 28a, terminating in the inwardly directed wall of the link and merging into the orifice 27a. The orifice 27a is of a size slightly larger than the pins connecting the individual links. In order to ensure against accidental displacement of the pin 22 from the orifice 27a, the slit 28a may be formed oversize, and then the end 26a bent backwards to constrict the slit 28a to the size of a gauge which is slightly less than the diameter of the pin 22, or the slit 28a may be formed undersize and expanded by a templet or gauge to the proper size, which will just clear the pin 22 with some amount of friction.

It will be understood that the construction illustrated in Figure 5, for forming the clasp, is

best suitable in connection with the plastic materials, such as phenol formaldehyde condensation resin, urea resin or other similar synthetic materials and plastics.

Though the construction provided and illustrated is best suitable for the purpose of making circlets in the form of bracelets or necklaces, it will be understood that any form of ornamental jewelry may be so made where flexibility is desired by a linkage arrangement. This linkage arrangement permits a fairly uniform contour of material made from independent links without extraneous metal showing, thus permitting a wide variety of color schemes, due to the coloration of the individual links. Where such linked elements form a single chain, the clasp described may be used to attach the linkage to a mounting of some character, such as an earring clamp or brooch pin. The construction as provided permits the use of the assembly of highly ornamental materials, without the necessity for introducing expensive or cumbersome settings, thereby exposing the ornamental material to the fullest extent. In this direction, particularly in the form of a circlet such as a bracelet or necklace, the clasp construction facilitates the opening of the circlet for attachment or detachment from the wrist or neck with the minimum effort and with great facility, and at the same time, providing sufficient security to avoid accidental displacement.

Having thus described my invention and illustrated its use, what I claim as new and desire to secure by Letters Patent, is—

1. A bracelet comprising a plurality of link members arranged in overlapping relationship forming a circlet, alternate links providing bifurcations into which the others of said links interfit, common pivots for said links passing through orifices in said links at their adjacent overlapping portions, and spaced from the ends thereof leaving projections, a clasp for said bracelet formed by laterally extending a slit into one of said links from a wall thereof and merging into the corresponding orifice and directed towards the inner face of said circlet, said slit being formed with means for retaining said pivot therein, and disengageable therefrom by tilting said projecting ends into manually accessible position.

2. A bracelet or the like circlet comprising a plurality of arcuately shaped links each formed with a pair of orifices longitudinally of the axis of the circlet, and spaced from the ends thereof to leave a projecting end of greater length than the thickness of the link, said links interfitting in overlapping relationship, alternate pairs of links forming bifurcations into which adjacent links fit, pins connecting said links passing through said orifices of the links forming the bifurcations and interfitting link respectively, whereby flexibility in contour may be obtained, and a connecting clasp formed from one of said links and its engaging pin comprising an inwardly directed slit in the side wall of said link connecting with an orifice whereby tilting of said last mentioned link extends the projecting ends into position accessible for manually disengaging the same from the connecting pin and resilient means adjacent the slit for retaining the pin.

3. A bracelet or the like circlet comprising a plurality of arcuately shaped links each formed with a pair of orifices longitudinally of the axis of the circlet, and spaced from the ends thereof to leave a projecting end of greater length than the thickness of the link, said links interfitting in overlapping relationship, alternate pairs of

- links forming bifurcations into which adjacent links fit, pins connecting said links passing through said orifices of the links forming the bifurcations and interfitting link, whereby flexibility in contour may be obtained, and a connecting clasp formed in one of said links comprising an inwardly directed slit connecting with an orifice, resilient means adjacent the walls of said slit whereby tilting of said last mentioned link extends the projecting ends for manually disengaging the same from the connecting pin, the resilient means providing frictional resistance to entrance and exit of said pin through said slit. 5
4. A clasp for jewelry of the character described, comprising links arranged in bifurcated and interfitting overlapping relationship including a common connecting pin for said overlapping sections passing through orifices spaced from the ends of the links and providing projecting ends, one of said links having an entrance slit connecting with an orifice on a lateral wall of said link, and frictionally engaging a pin and disengageable therefrom by tilting the link into manually accessible position. 10
5. A clasp for jewelry of the character described, comprising links arranged in bifurcated and interfitting overlapping relationship including a common connecting pin for said overlapping sections passing through orifices provided in and spaced from the ends of said links and providing projecting ends, one of said links having an entrance slit connecting with an orifice on a lateral wall of said link, and resilient means forming a frictional closure for said slit. 15
6. A clasp for jewelry of the character described, comprising links arranged in bifurcated and interfitting overlapping relationship including a common connecting pin for said overlapping sections passing through orifices provided in and spaced from the ends of said links and providing projecting ends, an orifice of one of said links loosely engaging said pin and having an entrance slit connected therewith snugly engaging said pin and formed on a lateral wall of said link. 20
7. A clasp for jewelry of the character described, comprising links arranged in bifurcated and interfitting overlapping relationship including a common connecting pin for said overlapping sections passing through orifices provided in and spaced from the ends of said links and providing projecting ends, one of said links having an entrance slit connecting with an orifice on a lateral wall of said link, a sheathing for the end of said last mentioned link including a portion looped within said slit forming a restricted entrance thereto. 25
8. A clasp for jewelry of the character described, comprising links arranged in bifurcated and interfitting overlapping relationship including a common connecting pin for said overlapping sections passing through orifices provided in and spaced from the ends of said links and providing projecting ends, one of said links having an entrance slit connecting with an orifice on a lateral wall of said link, a sheathing for the end of said last mentioned link including a portion extending within said slit and resiliently restricting said slit. 30
9. A bracelet or circlet of a plurality of link elements formed of a plastic composition, said link elements being arranged in overlapping relationship to form a circlet, alternate links providing bifurcations into which other links interfit, aligned orifices formed in said links adjacent the overlap leaving projecting ends, pins connecting said links passing through said orifices, and a clasp for said circlet, formed by slitting the link adjacent one of said orifices to provide an entrance in a lateral wall of said link, means for resiliently retaining the pin in said orifice and disengageable therefrom by tilting the projecting ends into manually accessible position. 35
